UNITED STATES PATENT OFFICE.

JOSEPH K. CHUN FAT, ABOARD THE U. S. S. BEAVER.

WATER-TIGHT VENTILATOR FOR SHIPS.

1,414,560.

Specification of Letters Patent.

Patented May 2, 1922.

Application filed October 24, 1921. Serial No. 510,126.

To all whom it may concern:

Be it known that I, JOSEPH KEO CHUN FAT, a citizen of the United States, residing aboard U. S. S. *Beaver*, have invented certain new and useful Improvements in Water-Tight Ventilators for Ships; and I do hereby declare the following to be a full, clear, and exact description of the invention, such as will enable others skilled in the art 10 to which it appertains to make and use the same.

This invention relates to new and useful improvements in ventilating devices and particularly to ventilating devices for ships.

15 One object of the invention is to provide a ventilating device having a valve which is adapted to be held in open position for the passage of air, but which will be automatically closed when water begins to pass into 20 the ventilator, due to high seas, rain, or other causes.

Another object is to provide a ventilator valve which is arranged to be normally held in open ventilating position, and which is 25 adapted to be released from the holding means by an electrical device, the circuit of which is closed by water passing into the ventilator, the valve being then automatically latched into closed position.

30 Other objects and advantages will be apparent from the following description when taken in connection with the accompanying drawings.

In the drawings:

35 Figure 1 is a side elevation of the ventilator pipe showing the external portions of the invention applied thereto.

Figure 2 is a vertical transverse sectional view through the pipe, on the line 2—2 of 40 Figure 1, showing the valve in elevation, and in closed position.

Figure 3 is a similar sectional view, but showing the valve in open position.

Figure 4 is a vertical longitudinal central 45 sectional view through the pipe and valve, taken on the line 4—4 of Figure 2.

Figure 5 is a sectional view similar to Figure 4, but taken on the line 5—5 of Figure 3, showing the position of the parts with the 50 valve open.

Figure 6 is an enlarged horizontal sectional view on the line 6—6 of Figure 5, showing the positions of the wires and their exposed ends which the water overflows to 55 close the circuit.

Fig. 7 is a diagram of the wiring.

In the ventilating systems in ships, especially below decks, the air pipes are passed through the bulkheads. Other ventilator pipes are extended through the port-holes. 60 In either arrangement of the pipes water gets into the pipes and passes from one compartment to another, with the result that the ship will become flooded.

The particular object of the present invention is to provide a means for closing the valve in the ventilator pipe when a sufficient amount of water has entered, and thus prevent the entrance of more water. The invention also contemplates the use of a detent 70 for holding the valve in open position for the free passage of air, but which is arranged to be released automatically by an electro-magnetic means, the circuit through which is closed by the entering water.

Referring particularly to the accompanying drawings, 10 represents a ventilator pipe which is properly supported through an opening in the bulkhead 11, the pipe having a drop or offset portion 12, arranged below 80 the plane of the main portion of the pipe. Pivoted centrally in the main portion of the pipe, adjacent the offset portion, is a disk 13, the shaft 14 of which having a spring 15 which normally urges the disk into vertical 85 position to close the passage of air through the pipe. Carried by one face of the disk are the right angularly extending, and parallel metal legs 16, each having its free end formed with a contact point 17. Mounted 90 in the pipe, in position to receive the said points of the legs 16, are the stationary contact sockets 18, disposed within the block of insulation 19. From the contact sockets 18 wires 20 and 21 extend, respectively, through 95 an electro-magnet 22, and to one side of a source of current 23, by means of the switch 24. A wire 25 connects the switch with one side of the source of current, while a wire 26 leads from the other side of the source. Pivotedly mounted on a suitable block 27, in the pipe, and adjacent the first block 19, is a detent hook 28, which is arranged to engage with the edge of the disk 13, when the disk is in horizontal position, as shown in Figure 105 5, a coil spring 29 being connected to the detent and the block to normally urge the detent into disk engaging position. Secured to the rear portion of the detent, and extending downwardly away from the detent, is a 110 curved arm 30 having an armature plate 31 on its free end for movement toward and

away from the electromagnet 22. When the armature plate is attracted by the electromagnet, the detent will be released from the disk, and the disk rocked into closed position 5 by its spring 15. In the offset portion of the pipe is disposed an insulated member 31 in which the ends of the wires 20 and 26 are embedded and have their tips exposed for contact by water which might enter the pipe, 10 and through which the circuit is closed to energize the electro-magnet. A pivoted, spring pressed detent 32 is mounted adjacent the detent 28, for engagement with a flange 15 33, carried by the disk 13, to hold the disk against accidental opening movement, after 20 having been closed by the electro-magnet. The shaft of the disk is provided with a knob or handle 34, disposed externally of the pipe, to permit resetting the disk in open position. Stops 35 are secured to the upper and lower portions of the pipe for the disk, 25 to limit the closing movement thereof. A stop 36 is also provided to prevent the disk moving too far when set into engaging position with the detent 28.

Thus, when the switch is closed, and the disk properly engaged with the detent 28, air will pass freely through the ventilator pipe, but should water enter the pipe, such 30 water would settle in a small pool in the offset portion of the pipe and cover the exposed ends of the wires 20 and 26, with the result that the circuit would be closed and the electro-magnet energized. The armature 35 plate 31 would be attracted to the electromagnet so that the detent 28 would be disengaged from the disk, and the disk permitted to close the passage through the pipe. Thus any great amount of water which 40 might get into one compartment would be prevented from flowing into the next compartment and flooding the vessel. This is also valuable where the ventilator is disposed in a port-hole, to exclude water from 45 the spray, or rain.

It will be noted that the disk is adapted to be closed before the level of the water can rise to attack the detents and other parts associated with the disk.

It will be further noted that when the 50 disk is move into closed position, the legs 16 are disengaged from the socket contacts, and the circuit broken.

Connected to the detent 32, and extending through the bottom wall of the main portion of the ventilator pipe, is a releasing cord of wire 37, so that when the disk is to be reset into open position, the detent may be moved from engagement with the flange 33, to permit the disk to be rotated by the 60 handle or knob 34.

What is claimed is:

1. In an automatic ventilator valve, the combination with a ventilator pipe having a downwardly offset portion, a pivoted disk 65 for closing the passage through the pipe, means for holding the valve in open position, an electro-magnetic means for releasing the holding means, and an electric circuit for energizing the electro-magnetic 70 means arranged to be closed by water entering the ventilator pipe through the offset portion.

2. In an automatic ventilator for ships, the combination with a ventilator pipe having a downwardly offset portion, a pivoted 75 spring closed disk in the pipe, means for holding the disk in open position, a normally open circuit arranged to be closed by the bridging of water thereacross, electro-magnetic means in said circuit to release the 80 said holding means and means for holding the disk in closed position.

3. In an automatic ventilator for ships, the combination with a ventilator pipe, a 85 rotary disk valve in the pipe and normally urged toward closed position, a detent for holding the disk in open position, an electric circuit normally open and arranged to be closed by the bridging of water, an armature on the detent, and a circuit breaker on 90 the disk.

In testimony whereof, I affix my signature, in the presence of two witnesses.

JOSEPH K. CHUN FAT.
